CLAIM

The ornamental design for a body for a juice extractor, as shown and described.

DESCRIPTION

FIG. 1 is a top, front, axonometric view of a body for a juice extractor showing our new design.

FIG. 2 is a front view thereof.

FIG. 3 is a rear view thereof.

FIG. 4 is a left side view thereof.

FIG. 5 is a right side view thereof.

FIG. 6 is a top plan view thereof; and,

FIG. 7 is a bottom plan view thereof.

The broken lines in the figures represent features of the article of manufacture that form no part of the claimed design.
